(57) **CLAIM**

We claim, the ornamental design for a grab handle, as shown and described.

DESCRIPTION

FIG. 1 is a front perspective view of a grab handle, showing an embodiment of our new design;

FIG. 2 is a top plan view of the embodiment shown in FIG. 1;
FIG. 3 is a right elevation view of the embodiment shown in FIG. 1;

FIG. 4 is a front elevation view of the embodiment shown in FIG. 1;

FIG. 5 is a rear elevation view of the embodiment shown in FIG. 1;

FIG. 6 is a left elevation view of the embodiment shown in FIG. 1; and

FIG. 7 is a bottom plan view of the embodiment shown in FIG. 1;

FIG. 8 is a front perspective view of a grab handle, showing another embodiment of our new design;

FIG. 9 is a top plan view of the embodiment shown in FIG. 8;
FIG. 10 is a right elevation view of the embodiment shown in FIG. 8;

FIG. 11 is a front elevation view of the embodiment shown in FIG. 8;

FIG. 12 is a rear elevation view of the embodiment shown in FIG. 8;

FIG. 13 is a left elevation view of the embodiment shown in FIG. 8; and,

FIG. 14 is a bottom plan view of the embodiment shown in FIG. 8.

The broken lines shown represent unclaimed subject matter and form no part of the claimed design.

1 Claim, 6 Drawing Sheets
